Primary Examiner — Melanie Pellegrini

(57)

CLAIM

The ornamental design for a pendant as shown and described.

DESCRIPTION

1. Pendant

1.1 : Front

1.2 : Back

1.3 : Left

1.4 : Right

1.5 : Top

1.6 : Bottom

1.7 : Perspective

The design consists of a pendant with two parallel rows of cubes; a row of diamonds is placed between the parallel rows of cubes; all the angles on the sides of the faces of the cubes are cut at 45 degrees.
